UNITED STATES PATENT OFFICE.

ROBERT C. LEGAT, OF NEW BRITAIN, CONNECTICUT.

SAFETY DEVICE FOR PUNCH-PRESSES.

1,164,943.

Specification of Letters Patent. Patented Dec. 21, 1915.

Application filed December 23, 1914. Serial No. 878,719.

To all whom it may concern:

Be it known that I, ROBERT C. LEGAT, a citizen of the United States, residing at New Britain, in the county of Hartford and State of Connecticut, have invented certain new and useful Improvements in Safety Devices for Punch-Presses, of which the following is a specification.

My invention relates to improvements in safety devices for punch presses and the object of my improvement is to provide means for preventing injury to the operator of a punch press and at the same time to effect delivery of the work operated upon by the same.

In the accompanying drawing: Figure 1 is a front elevation of a punch press equipped with my improved safety device, the press being of the open back power type. Fig. 2 is a similar view of a foot press similarly equipped. Fig. 3 is a similar view on an enlarged scale of part of the press shown in Fig. 2. Fig. 4 is a side elevation of the same. Fig. 5 is a front elevation of the safety device shown in Figs. 3 and 4 removed from the press. Fig. 6 is a side elevation of the same. Fig. 7 is a plan view of the same. Fig. 8 is a similar view of the same, with the movable parts in a different position from that shown in Fig. 7. Fig. 9 is a view corresponding to Fig. 4 showing a press equipped with a stripper and having a modified means of operating the safety device. Fig. 10 is a plan view of part of the same.

The various styles of presses comprise each a plunger 10 carrying the movable dies 11 and co-operating therewith a bed 12 supporting the fixed die 13, the latter being secured to a plate 14, and the plate 14 being secured to the bed 12 in proper position by means of studs and nuts or by bolts 15.

My safety device comprises a swinging guard plate or shield 16, pivotally mounted at one side, as shown the left side, on a vertical post 17 extending upwardly from a base plate 18, the latter being secured to the plate 14 by means of one of the bolts 15, and provided with a positioning spring 19, which as shown is mounted on the post 17.

The shield 16 is made of heavy sheet metal and comprises a main portion 20 of rectangular form, normally positioned directly over the fixed die 13, and at an appreciable angle or inclination relatively thereto and at the end from which it is supported the shield 16 is provided with a forwardly extending wing

21, having laterally overhanging knuckles 22, suitable for engagement with the post 17.

As shown the knuckles 22 are positioned at the upper and lower ends of the wing 21 and the spring 19 is positioned between them. One end of the spring 19 is secured to the post 17 and the free end is hooked over the wing 21.

A stop 23 limits the rearward movement of the shield 16 and as shown consists of an upward projection at the rear end of a collar 24, adjustably mounted on the post 17 and secured by means of a set screw 25, and engaging with the wing 21.

The main portion 20 constitutes the guard proper, and is in the form of a plane, inclined from the upper end rearwardly, and exposing the work at the lower and rear portion, and the extent of the said main portion is such that an inclined wall is opposed to every part of the plunger 10. Furthermore, the amount of inclination of the said main part 20 is such that when in the downward movement of the plunger 10 any part thereof engages with the main part 20 the effect of such engagement is to tend to move the main part 20 forwardly, in opposition to the spring 19, and as the movement is continued downwardly the main part 20 is moved forwardly entirely clear of the work and so that the movable die 11 engages in proper manner with the lower fixed die 13. Upon the return, upward movement of the plunger 10 the spring 19 returns the shield 16 to the normal position, over the lower die 13. Accordingly, in placing the work, the hand is housed within the shield 16 and effectively guarded thereby from any liability of being caught by the plunger 10 and in case the hand is not removed by the operator before the downward movement of the plunger the hand is pushed forwardly out of the way by the shield 16 when the same is moved forwardly in the manner described.

In the modification shown in Fig. 9 the plunger 10 engages directly with the shield 16 to push the same out of the way. In the style shown in Fig. 1 a stop or lug 26 on the plunger frame 27 engages with the shield 16. In the style shown in Figs. 2, 3, and 4 a roller 26^a is provided for the purpose mentioned.

I prefer to position the lug 26 or roller 26^a so as to engage with the main part 20 adjacent the post 17 and this portion of the

main part 20 is made plane so as to provide a way suitable for coöperating with the said lug or roller. The portion of the main part 20 remote from the way portion mentioned and which does not come in contact with any part of the plunger 10 may be provided with holes 28 to admit light to the work and the lower die 13.

The lower knuckle 22 rests on the collar 24, so that the position of the shield 16 as regards elevation relatively to the lower die 13 is determined by the position of the said collar 24. Accordingly, raising and lowering the collar 24 on the post 17 raises and lowers the shield 16, and turning the collar 24 on the said post 17 changes the normal angular position of the same.

In some cases a stripper is used. In the form shown in Fig. 9 the stripper 29 is suitably positioned to strip the work from the upper die 11, being pivotally mounted on a shaft 30 and limited in its upward movement by a stop 31, and normally held against the said stop by a spring, or counterweight, not shown. The work in this case is of such character that after being operated upon by the dies it sticks to the upper die and is lifted thereby when the same is returned to the normal upper position. Furthermore, as is usual and well known in the art, only a small portion of the work is engaged by the dies, and the operative portion of the dies is confined to the central portion thereof, designated by the character 32, and which is relatively limited in extent.

So far as the operation of my invention is concerned the upper surface of the lower die 13 is a plane surface. In the case of the upper die 11, the same comprises the central portion 32 of the particular form suited to the work, and which is shown as square in the drawing, and which extends downwardly from the body portion of the upper die 11. The body portion 33 of the plunger 10 overhangs the upper die 11. In some cases the said body portion 33 engages the stripper 29 on the downward movement and carries the same along during the latter portion of the said downward movement and the stripper 29 returns therewith on the return upward movement until limited by the stop 31, as mentioned. However this may be, the work overhangs the upper die 11 or the central operative portion 32 thereof suitably to be forcibly removed from the upper die 11 by the stripper 29 when the latter has reached its final uppermost position. As shown the stripper 29 consists of a plate having a U shaped opening suitable to admit the upper die 11, the side arms 35 of which plate are suitably spread apart to engage with the laterally overhanging portion of the work, all of which is quite ordinary.

It will be noted however as shown in Fig. 9 that the normal position of the stripper 29,

as determined by the relative positions of the shaft 30 and the stop 31, is such that the same is slightly above the inclined main portion of the shield 16. Because of this the shield 16 is returned to the normal position 70 as shown in the said figure just before the work is stripped from the upper die 11 and when the work is stripped therefrom the same is dropped onto the said main portion 20, and is delivered to the rear portion of the lower die 13, and clear of the front and operative portion of the same. As a matter of fact the work is stripped with some force so that the same is actually thrown downwardly with some force and will be delivered 75 to the space at the rear of the lower die. In some cases a stripper is not required, as when a simple stamping operation is effected, and the work is left on some portion of the lower die 13, adjacent the operative portion 80 thereof. In such case the shield 16 is sufficiently close to the lower die 13 so that the lower edge 34 thereof, which sweeps over the upper surface of the said lower die 13, will strike the work after being operated upon 85 and brush the same off the lower die and deliver the work to the space to the rear of the said die. In either of the cases mentioned the shield 16 serves to deliver the work clear 90 of the operative portion of the die, so that a new piece of work may be placed in the die by the operator without any attention being required on the part of the operator to the work that was previously operated upon, and in both cases the said shield serves 95 100 as a guard or safety device to protect the hand of the operator in placing the work in the die.

What I claim as my invention is:

1. A safety device for punch presses comprising a plate positioned between the upper and lower dies and in a plane that is at an inclination to the line of movement of the upper die, and the said plate being mounted by one end on a vertical shaft suitably to be 105 pushed to one side of the said line of movement by the said upper die.

2. A safety device for punch presses comprising a shield having a plate-like body portion suitable to be positioned at an inclination to the line of movement of the movable die, and a supporting wing at one end thereof, a vertically directed pivotal support for the said wing, and spring operated positioning means connected to the said 115 120 shield.

3. A safety device for punch presses comprising a post, a shield having a set of knuckles mounted on the said post, a collar mounted on the said post and having means 125 for being secured in different positions thereon, the lowermost of the said knuckles being supported by the said collar, and a projection on one end portion of the said collar and suitably positioned to engage with 130

the said shield and limit the movement thereof in one direction.

4. A safety device for punch presses comprising a shield having a portion positioned normally at an inclination across the line of movement of the upper die, one part of the said inclined portion serving as a way in engagement with the said upper die, and the part of the said inclined portion remote 10 from the said way being provided with a plurality of perforations suitable for admitting light to the lower die.

5. In combination, a punch press having a fixed lower die, a movable upper die, a shield having an inclined portion positioned normally across the line of movement of the said upper die, and supported suitably to be pushed aside by the said upper die, spring means tending to bring the said shield to the 20 normal position, a stripper having a limited upward movement, and the said stripper being positioned normally slightly above the said inclined portion.

6. A safety device for punch presses comprising a shield having a body portion of plate-like form positioned at an inclination to the line of movement of the upper die, and vertically directed supporting means at

one end thereof, and a portion of the said body portion being suitable to serve as a 30 way in coöperation with the said upper die.

7. A safety device for punch presses comprising a shield made of sheet material, the said sheet material being bent to form two parts, one of the said parts serving as a supporting wing, positioned in a vertical plane, and having means for being pivotally supported on a vertical shaft, and the other of the said parts serving as the shield proper, being in the form of a plate of suitable size 40 and form to extend across the space between the upper and lower dies, and at an inclination to the line of movement of the said upper die suitably to be engaged by the said upper die, and spring means tending to hold 45 the said shield so that the said shield proper will extend across the said space between the said dies, and to restore the said shield to such position after having been moved therefrom by reason of engagement with 50 the said upper die.
